OTHER PUBLICATIONS

Trinkums, Stemware Adornments, undated product.
 Color copies of seven (7) photographs of various commercially available prior art stemware adornments (undated).

Primary Examiner—M. N. Pandozzi

(74) Attorney, Agent, or Firm—Boyle, Fredrickson, Newholm, Stein & Gratz, S.C.

(57) **CLAIM**

The ornamental design for a stemware adornment, as shown and described.

DESCRIPTION

FIG. 1 is a perspective view

FIG. 2 is a left side elevation view.

FIG. 3 is a right side elevation view.

FIG. 4 is a front elevation view.

FIG. 5 is a rear elevation view.

FIG. 6 is a top plan view; and,

FIG. 7 is a bottom plan view.
